UNITED STATES PATENT OFFICE.

CHESTER J. WELSH, OF CONNEAUT, OHIO.

SHOE RACK.

Application filed November 5, 1927. Serial No. 231,167.

The present application, as indicated, relates to a shoe rack, and more specifically to a rack adapted to be hung on a wall or similar structure and to support a pair or 5 pairs of shoes out of contact with said wall or like member. The primary object of the invention is to provide a very simple and inexpensive article of the character described which shall provide a means for keeping 10 shoes off the floor and for preventing damaging contact of the shoes with the wall or other supporting member. To the accomplishment of the foregoing and related ends, said invention, then, consists of the means 15 hereinafter fully described and particularly pointed out in the claim.

The annexed drawing and the following description set forth in detail certain mechanism embodying the invention, such 20 closed means constituting, however, but one of various mechanical forms in which the principle of the invention may be used.

In said annexed drawing:

Fig. 1 is a perspective view of the rack 25 contemplated by the present invention; and Fig. 2 is an end elevation thereof showing a shoe supported in the rack.

Referring more particularly to the drawings, the reference numeral 1 indicates generally a rack contemplated by the present invention which comprises a single wire 2 bent into the desired shape. At a point somewhat removed from one end of the wire there is formed a right angle bend 3, and a second 35 right angle bend 4 defines a short spacing section 5. A support portion 6 is provided at a point approximately midway of its length with a U-shaped loop or eye 7, and at the end farthest removed from the bend 40 4 with a right angle bend 8 defining, in connection with a second right angle bend 9, a second spacing portion 10 parallel to, and equal in length to the spacing portion 5. From the bend 9, the wire extends in a plane 45 parallel to the plane of the eye 7 to form one leg 11 of a V-shaped rest defined by said leg 11, a second leg 12, and a bend 13. A second V-shaped rest is then formed by bending the wire as at 14 and 15 to form the legs 16 50 and 17. At the remote end of the leg 17 there is formed a right angle bend 18 similar to the bend 9, and thence the wire continues in a spacing portion 19 similar to the portion 10, a right angle bend 20 similar 55 to the bend 8, a support 21 similar to

the support 6 and provided with an eye 22 similar to the eye 7, a bend 23, spacing portion 24, bend 25, and cross-bar 26 analogous to the bend 4, spacing portion 5, bend 3, and portion 2, respectively, heretofore described. 60

From the above description it will be noted that the supports 6 and 21 are provided with inwardly extending loops or eyes 7 and 22 respectively, and that the supports and their eyes lie in a single plane; and that the rest-forming legs 11, 12, 16, and 17, are spaced from the supports 6 and 21 and lie in a plane parallel to the plane of said supports; and that the cross-bars 2 and 26 are likewise spaced from said supports 6 and 21 and lie 70 in the plane of the rest-forming legs. The ends 27 and 28 of the cross-bars 2 and 26 respectively lie in close relation to each other after the rack has been formed, and a tubular joint member 29 is provided to receive both 75 of said adjacent ends 27 and 28 to secure said ends in the desired position.

In use, the supports 6 and 21 are adapted to be secured to a wall or like member 30 by means of screws or similar fastening means 80 31 passing through said eyes 7 and 22 and secured in said wall. When the rack is so secured to the wall, it will be obvious that the V-shaped rests are materially spaced from the wall and that the cross-bars 2 and 26 are 85 spaced a like distance therefrom. Consequently, a shoe 32 may be supported on said rack with its heel 33 engaged between the legs 11 and 12 or 16 and 17 and with its sole 34 resting against the cross-bar 2 or 26. This 90 arrangement holds the shoe positively away from the wall and prevents scarring or soiling of the wall surface by the hard and dirty bottom surface of the shoes.

Of course it is to be understood that the 95 rack disclosed in the present specification might as well be formed with any number of V-shaped supports to carry any number of pairs of shoes. Moreover it is to be understood that I do not limit myself to the particular type of securing means illustrated and described for the opposed ends of the wire frame, but that I might weld or solder these ends together or fasten them together in any other well known manner. It will also be 100 obvious that the eyes 7 might be separate pieces welded or otherwise secured to the legs 6 rather than being formed integrally therewith.

Other modes of applying the principle of 110

my invention may be employed instead of the one explained, change being made as regards the mechanism herein disclosed, provided the means stated by the following claim 5 or the equivalent of such stated means be employed.

I therefore particularly point out and distinctly claim as my invention:

A shoe-rack comprising a single strand of 10 wire, said wire being bent to form a pair of supports each of which is provided with an eye intermediate its ends, a pair of V-shaped rests spaced from said supports by connecting portions formed at right angles to said

supports at one end thereof, said rests lying in a plane parallel to the plane of said supports, and a pair of substantially meeting cross-bars spaced from said supports by connecting portions formed at right angles to said support at the other end thereof, said cross-bars being disposed in the vertical plane including said rests, in combination with a tubular member receiving in its opposite ends 25 and joining the adjacent ends of said cross-bars.

Signed by me this 3rd day of November, 1927.

CHESTER J. WELSH.
